GARDEN TOOL

Joseph A. Fraim, Norfolk, Va.

Application October 25, 1948, Serial No. 149,279

Term of patent 7 years

(Cl. D35—2)

To all whom it may concern:

Be it known that I, Joseph A. Fraim, a citizen of the United States of America, residing at Norfolk, in the county of Norfolk and State of Virginia, have invented a new, original, and ornamental Design for a Garden Tool, of which the following is a specification, reference being had to the accompanying drawing, forming part thereof.

Figure 1 is a front elevational view of a garden tool showing my new design.

Fig. 2 is a side elevational view.

Fig. 3 is a plan view of the tool.

I claim:

The ornamental design for a garden tool, as shown.

JOSEPH A. FRAIM.
